INHALANT DISPENSER

John V. Ryden, Summit, N.J., assignor to
Schering Corporation, Bloomfield, N.J.

Filed Dec. 10, 1969, Ser. No. 20,426

Term of patent 14 years

Int. Cl. D24—05

U.S. Cl. D83—1

FIG. 1

FIG. 2

FIG. 3

FIG. 4

FIG. 5

FIG. 6

FIG. 7

FIG. 8

FIG. 9

FIG. 10

FIG. 1 is a perspective view of an inhalant dispenser embodying my new design with hood closed;

FIG. 2 is a top plan view of the inhalant dispenser of FIG. 1;

FIG. 3 is a front elevational view of the inhalant dispenser of FIG. 1;

FIG. 4 is a side elevational view of the inhalant dispenser of FIG. 1;

FIG. 5 is a rear elevational view of the inhalant dispenser of FIG. 1;

FIG. 6 is a perspective view of an inhalant dispenser embodying my design with the hood open;

FIG. 7 is a top plan view of the inhalant dispenser of FIG. 6;

FIG. 8 is a front elevational view of the inhalant dispenser of FIG. 6;

FIG. 9 is a side elevational view of the inhalant dispenser of FIG. 6; and

FIG. 10 is a rear elevational view of the inhalant dispenser of FIG. 6.

I claim:

The ornamental design for an inhalant dispenser, as shown and described.
